ANIMAL FIGURE PLAYGROUND DEVICE

Hubert H. Hansen, Coral Gables, Fla., assignor to Fun In The Sun of Florida, Inc., Miami, Fla., a corporation of Florida

Filed Nov. 17, 1961, Ser. No. 67,579

Term of patent 14 years

(Cl. D34—15)

FIG. 1

FIG. 2

FIG. 3

FIG. 1 is a side elevation of an animal figure playground device, showing my new design.

FIG. 2 is a front elevation thereof.

FIG. 3 is a rear elevation thereof.

FIG. 4 is a top plan view thereof.

The dominant features of the design are shown in full lines.

I claim:

The ornamental design for an animal figure playground device, as shown and described.
